The ornamental design for a desk phone, as shown and described.

DESCRIPTION

FIG. 1 is a front-right perspective view of a desk phone, showing our new design;

FIG. 2 is a top-left-back perspective view thereof;

FIG. 3 is a bottom view thereof;

FIG. 4 is a top view thereof;

FIG. 5 is a left-side view thereof;

FIG. 6 is a right-side view thereof;

FIG. 7 is a front view thereof; and,

FIG. 8 is a back view thereof.

The broken lines in FIGS. 1-8 depict portions of the desk phone that form no part of the claimed Design.

The thin, black lines shown in long dashes with intermittent breaks are shading and/or tangent lines to show contour of the surfaces or curved edges of a desk phone, and do not actually appear on the surface of the device.
